UNITED STATES PATENT OFFICE

157,085

CHILD'S STROLLER

Harold R. Pinkerton, Seattle, Wash., assignor to Caldwick and Evans, Seattle, Wash., a partnership

Application January 31, 1949, Serial No. 589

Term of patent 3½ years

(Cl. D14—14)

To all whom it may concern:

Be it known that I, Harold R. Pinkerton, a citizen of the United States, residing at Seattle, in the county of King and State of Washington, have invented a new, original, and ornamental Design for Child's Stroller, of which the following is a specification, reference being had to the accompanying drawing, forming part thereof:

Fig. 1 is a perspective view of a child's stroller showing my new design.

Fig. 2 is a side elevation of the same.

Fig. 3 is a front elevation.

I claim:

The ornamental design for a child's stroller, as shown.

HAROLD R. PINKERTON.
